UNITED STATES PATENT OFFICE

THOMAS J. SCHINDLER AND WILLIAM F. BRADLEY, OF ROCK ISLAND, ILLINOIS; SAID SCHINDLER ASSIGNOR TO SAID BRADLEY

AUTOMOBILE RADIATOR CONDENSER

Application filed January 23, 1931. Serial No. 510,736.

Our invention has reference to an automobile radiator condenser, and has for its chief purpose to prevent a high temperature in the water and other contents of the cooling system of an automobile or truck. In cooler temperatures, where it is found necessary to provide the cooling system with alcohol or other anti-freeze products, such products are liable to evaporate more or less with the water until the mixture is below the safety point, and a sudden drop in the outside atmosphere will cause the radiator to freeze up. This is particularly the case with trucks, in which the water is very easily brought to the boiling point while they are being operated. By the use of the present invention steam or other vapor formed in the radiator is condensed and returned thereto in a cooled condition, and the temperature of the liquid contents of the radiator kept at or near an established point. As a result there is little or no evaporation, and the same filling of alcohol will be sufficient for the entire season, or longer.

Another purpose of the invention is to provide means for preventing a sudden discharge of water or steam through the device.

The above named, and other features and advantages of the invention will more fully appear from the following specification, reference being had to the drawings accompanying the same, in which:—

Fig. 1 shows the invention as it appears when in use.

Fig. 2 is a longitudinal section of the post 5 and related parts.

Fig. 3 is a similar view of a modified form of the device.

In Fig. 1 is indicated in broken lines the upper part of a radiator A, provided with a cap B, in which is supported a post 5, by means of a hollow stem 6 having a threaded connection with said cap. The upper end 7 of the passage in the stem is of reduced diameter and in the lower part of the passage there is fixed a pin 8 upon which rests a ball 9. Inserted in one side of the post 5 and opening into the recess 7 is a nipple 10, fitted with a coupling 11, in which is held the lower end 12 of a helical coil 13, the up-

per end 14 of which is connected with a passage 15 in the upper end of the post 5. A connection 16 is fixed in the upper end of said post, forming a continuation of the passage 15, and fitted with a coupling 17, with which is connected the upper end of an overflow pipe 18, which normally extends downwardly in front of the radiator. Said pipe has a pivotal connection, so that it can be swung upwardly into a horizontal position and rotated with the coil and radiator cap when it is desired to remove or return the same.

When the invention is in position on a radiator the vapor arising from the contents of the radiator will find its way into the lower end of the coil 13, where it will be condensed by the cool air around the coils, and the condensate returned to the radiator. In practice the vapor or steam will rarely rise more than half the height of the coil, but sufficient piping is provided to take care of any normal evaporation.

In the event of a sudden splurge of water or steam upwardly the ball 9 will be carried upwardly thereby and seated against the shoulder at the lower end of the recess 7, shutting off further movement of the water upwardly. The lower end of the connection 6 can also be provided with a cap 19, having an intake opening in its sides, which will interfere with any direct movement of the water upwardly into the lower end of the post. The post 5 not only forms a part of the condensing apparatus, but it provides a very substantial support for the coil.

In Fig. 3 is shown a form of the invention in which the post 5 is replaced by a cylindrical portion 20, in the upper end of which is tapped a plug 21, having an opening 22 communicating downwardly with a chamber 23, from which a passage 24 extends downwardly into a threaded stem 25, for connection with a radiator. In the lower end of said passage is a pin 26 and ball 27, for operation similarly to the ball 9. In the chamber 23 is a float 28, connected with a stem 29, on which is a valve 30, normally closing the passage 24. The lower end 12 of the coil is connected at the lower end of the cylinder 20, and the up-

per end 14 thereof is connected with a nipple 31 fixed in the plug 21. Fixed to the upper end of the nipple 31 is a cap 32, having an opening 33 beneath which is a ball 34, of a 5 diameter which will permit the escape of air through said opening when vapor enters the lower end of the coil, or the return of air therethrough in case the amount of vapor in the coil becomes less. Its action is that of a 10 breather. In the event of a sudden movement of water or steam upwardly through the cylinder 20, however, the ball 34 will be raised, closing the opening 33, and preventing the escape of such water or steam. In 15 case there should be an excessive amount of condensation, so that it would pass upwardly through the coil, as is likely to happen with large trucks or other vehicles having engines or large capacity, such condensation would 20 pass out of the top of the coil and downwardly into the chamber 23, and upon a sufficient amount collecting therein the float 28 will be raised thereby, elevating the valve 30, and permitting the products of condensation to 25 flow downwardly, and back into the radiator. The weight and valve are of sufficient weight to prevent the movement of vapor upwardly into the chamber 23.

Other changes in the form and arrangement of the invention can be made, without departing from the spirit thereof.

What we claim, and desire to secure by Letters Patent, is,

1. A device of the class described, comprising a central support, having passages in its ends and adapted for attachment with the radiator cap of a motor vehicle, with communications through the same, and a coil connected at its lower end with the passage in the lower end of said support, and at its upper end with the passage in the upper end of said support.

2. A device of the class described, comprising a coil, means for support of said coil on the radiator of a motor vehicle containing means of communication from said coil to the radiator, and a valve in said last named means adapted to be closed upon a sudden movement of liquid or fluid upwardly.

3. A device of the class described, comprising a coil supported on a radiator cap and communicating through the same, and an overflow pipe pivotally connected with the upper end of said coil, so as to be capable of being swung upwardly into a horizontal plane.

4. In a device of the class described, a support adapted for attachment to a radiator cap, and having a central passage, a coil connecting with said passage at the upper and lower ends thereof, a valve in said passage, normally closed, and a float for said valve, adapted for operation by an accumulation of liquid in said passage.

5. In a device of the class described, a

support adapted for attachment to the radiator cap of a motor vehicle, and having a central passage, a coil connecting with said passage at its ends, a valve in said passage normally closed, a float for said valve adapted for operation by an accumulation of liquid in said passage, and a check valve beneath said float valve, normally open, and adapted for closing by a sudden movement of liquid or fluid upwardly in said passage.

6. In a device of the class described, a support adapted for attachment to the radiator of a motor vehicle, and having a central passage, normally open at its upper end, a coil connecting with said support near its ends and communicating with said passage, a valve in said passage normally closed, a float for said valve operable by an accumulation of liquid in said passage, a check valve in the lower end of said passage, normally open, and a check valve in the upper end of said passage, normally open, and permitting free movement of air outwardly or inwardly under normal pressure.

In testimony whereof we affix our signatures.

THOMAS J. SCHINDLER.
WILLIAM F. BRADLEY.
